HERMAN E. WHITING, OF PALMYRA, NEW YORK, ASSIGNOR TO GARLOCK AUTO SPECIALTY COMPANY, OF PALMYRA, NEW YORK, A CORPORATION OF NEW YORK.

VAPORIZER FOR INTERNAL-COMBUSTION ENGINES.

1,130,228.

Specification of Letters Patent. Patented Mar. 2, 1915.

Application filed May 23, 1910. Serial No. 562,840.

To all whom it may concern:

Be it known that I, HERMAN E. WHITING, of Palmyra, in the county of Wayne and State of New York, have invented a certain new and useful Vaporizer for Internal-Combustion Engines, of which the following is a specification.

My invention has for its object the production of a particularly simple and efficient vaporizer or carbureter for internal combustion engines, in which the amount of liquid fuel to be mixed with air is varied correspondingly with the volumes of air passing through the vaporizer or carbureter during the opening and closing of the throttle valve; and to this end it consists in the combinations and constructions hereinafter set forth and claimed.

In describing this invention reference is had to the accompanying drawing in which like characters designate corresponding parts in all the views.

Figure 1 is a vertical, sectional view of one embodiment of my vaporizer, the throttle valve being shown as open. Fig. 2 is a view similar to Fig. 1, partly broken away and parts being omitted, showing the positions of the shiftable nozzle member and the throttle valve when said valve is partly closed.

In the illustrated embodiment of the invention 1 is the body or casing of the vaporizer or carbureter which contains a carbureting chamber having a conical or contracted wall 2. A fuel discharging nozzle is arranged in the carbureting chamber and may comprise a shiftable atomizing member 3 which shifts axially of a fixed member 4. The shiftable member 3 preferably is in the form of an open-ended sleeve surrounding the fixed member 4 and said member 4 slidably fits in the member 3, the upper open end of the latter forming the atomizing opening. A choke chamber 5 may surround the atomizing nozzle, and move with the member 3 in order that the exit end of the nozzle will be always located substantially at the narrowest portion of the choke chamber, and said choke chamber 5 in this instance is connected to the shiftable member 3 by suitable webs 6. The inner fixed member 4 of the atomizing nozzle preferably is carried by a bridge 7 extending across the air inlet passage 8 of the vaporizer or carbureter and the passage 9 of the nozzle

member may communicate at its lower end with a conduit or passage 10 extending lengthwise of the bridge 7.

The receiving member 11 for the liquid fuel may be the ordinary float chamber which communicates at its lower end at 12 with a suitable source of supply of fuel. The float 13 within the chamber tends to maintain the level of the fluid at substantially the exit end of the nozzle when the nozzle is in its lowermost position as shown in Fig. 1. The float chamber may however be dispensed with.

As here shown the conduit or passage 10 may communicate with a valve chamber 14 and the receiver 11 also may communicate with the chamber 14 through a conduit 15 which includes a stand pipe 16 extending upwardly into the valve chamber 14, the stand pipe 16 being of large diameter compared with the passage 10 and having a contracted exit end 17. The contracted stand pipe tends to hold back any solid matter in the fuel, and thus prevent the nozzle from becoming clogged. The valve chamber is located outside of the carbureting chamber and communicates therewith through a passage 18 at the upper end of the valve chamber.

In the illustrated construction a needle valve 19 is located within the chamber 14, for opening and closing the upper end of the stand pipe 16, the valve being held in its closed position by a spring 20 and being provided with a piston 21 fitting the valve chamber. During the suction strokes of the piston of the engine to which this vaporizer is attached, the valve 19 will be raised from its seat to permit the flow of the liquid fuel out of the stand pipe and into the passage or conduit 10.

A throttle valve 22 may be employed for controlling the flow through the carbureting chamber, the valve preferably having a stem 23 formed with a slotted head 24 in which works a pin 25 carried by a crank arm 26 mounted on a rock shaft 27 which extends outwardly through the body of the vaporizer and which is connected by a link 28 to a suitable operating handle not shown. The shaft 27 may also be connected to the choke chamber 5 and the movable member or section 3 of the nozzle in order that the throttle valve 22 and the choke chamber and the movable member of the nozzle 3 will be oper-

ated synchronously. These connections preferably comprise a link or pitman 29 having a strap or ring 30 at one end which incloses an eccentric cam 31 rigid with the rock shaft 27, and is connected at its other end to one arm of a lever 32, pivoted to a depending bracket on the body 1 at 33 between its ends, and the other arm of the lever is connected to a link 34 which is connected to a pin 35 extending into the base of the choke chamber through a slot 36 in the body 1. Obviously as the rock shaft 27 is operated, the throttle valve 22, and the choke chamber 5 and the movable member 3 of the nozzle will also be operated. However, it will be obvious that the choke chamber 5 may be omitted, and also that said choke chamber is not necessarily shiftable with the movable member of the nozzle.

20 I have here shown my vaporizer as embodying a purifying and mixing device, said device comprising preferably a dust catching chamber 37 located below the throttle valve 22 and around the mixing chamber 25 and filtering device 38 above the throttle valve 22. The dust catching chamber contains a suitable pad 39 in which a liquid is contained for catching the dust, and the filtering and mixing device 38 comprises 30 plates 40, 41 and 42 formed with openings having portions spaced apart and adapted to receive between them a filtering material as asbestos and the like. The throttle valve 22 preferably is formed cup shaped in order to 35 deflect the incoming charge downwardly into the dust catching chamber whence it passes upwardly around the valve through the filtering and mixing device through a chamber 43 in the upper part of the body, 40 thence out through a nipple 44 by means of which the body of the vaporizer communicates with the inlet pipe of the engine. It will be understood, however, the filtering device may be omitted and any other form of 45 throttle valve may be employed.

As here shown the upper portion of the body of the vaporizer, that is the portion confining the chamber 43 is detachable from the major part of the body and is secured thereto in any suitable manner such as ordinary lugs or ears (not shown). This arrangement permits the liquid to be inserted in the chamber 39.

The operation of the device is as follows: 55 Liquid fuel from the float chamber 11 passes by way of connection 15 through stand pipe 16, thence by conduit 10 through the fuel discharging nozzle 3, 4. The suction causes the air to pass through the inlet 8 into 60 the choke tube 5, which, owing to its contracted form, concentrates the air about the nozzle and causes carburization to take place. This charge, which necessarily contains a number of globules of gasoline, enters into 65 the bell-shaped throttle 22 which acts as a

baffle and causes the charge to return upon itself, thus producing a mixing action and breaking up a great many of the globules within the mixture. The heavy solid particles will be deflected by the baffle onto the 70 dust catching pad 39. After the mixture has been returned upon itself, it passes through the perforated chamber 38, the remaining globules being deposited on the walls of the openings in said chamber or being caught by the asbestos until sufficient air has mixed with the globules to vaporize them. The asbestos also acts to collect dust and, at the same time, is not consumed or burned by a back fire. The screen 41 prevents the back fire reaching the fuel discharging nozzle 3, 4. Of course, when the engine is started, the suction acts on the valve 19 to permit a flow of fuel to the nozzle. The nozzle is extensible and, in this 85 way, the supply therefrom may be made to correspond to the speed of the engine. The choke tube 5 is adjustable to correspond to the length of fuel discharge nozzle and the throttle valve 22 is also adjustable with the 90 fuel discharging nozzle, so that both of these parts are controlled simultaneously by the operator.

What I claim is:—

1. In a vaporizer, the combination with an extensible fuel discharging nozzle, of a choke chamber about the nozzle adjustable to correspond to the length of the fuel discharge nozzle.
2. In a vaporizer, the combination with a fuel discharge nozzle having an extensible portion provided with an atomizing opening, of a choke chamber surrounding the nozzle and connected to the extensible portion to be adjusted therewith.
3. In a vaporizer for internal combustion engines, a carbureting chamber, an atomizing nozzle for the liquid fuel extending into the carbureting chamber and including two members, one being extensible axially beyond the other for varying the height of the nozzle, a choke chamber around the nozzle and movable with the extensible member thereof, and means for moving the extensible member and the choke chamber, substantially as and for the purpose specified.
4. In a vaporizer, the combination with a fuel discharging nozzle arranged to discharge directly upward and a carbureting chamber into which the nozzle delivers, of a contracted wall in said carbureting chamber at a point above the discharge of the nozzle and in concentric relation to said discharge opening, and bell-shaped baffle arranged above said contracted wall so that the nozzle discharges directly at the center of the baffle, the baffle having a greater diameter than the contracted wall to cause the mixture to return upon itself.
5. In a vaporizer for internal combustion

engines, a carbureting chamber, an atomizing nozzle for liquid fuel extending into the carbureting chamber and including two members, one being extensible axially beyond the other for varying the height of the nozzle, a throttle valve for controlling the flow through the carbureting chamber, and means for moving the extensible member of the nozzle and for operating the valve 10 synchronously, substantially as and for the purpose described.

6. In a vaporizer for internal combustion engines, a carbureting chamber, an atomizing nozzle for the liquid fuel extending into the carbureting chamber and including two members, one being extensible axially beyond the other for varying the height of the nozzle, a choke chamber around the nozzle and movable with the extensible member, a 15 throttle valve for controlling the flow through the carbureting chamber, and means for moving the extensible member of the nozzle and the choke chamber and for operating the valve, substantially as and for the 20 purpose specified.

7. In a vaporizer for internal combustion engines, a mixing chamber, a valve chamber at one side of the mixing chamber and communicating therewith, an atomizing nozzle 25 extending into the mixing chamber, a conduit communicating with the nozzle and the valve chamber, an inlet for the liquid fuel opening into the valve chamber, and a valve in the valve chamber for normally closing the inlet conduit, the valve having a piston slidably fitting the valve chamber and movable to open the inlet conduit by the suction within the mixing chamber, substantially as and for the purpose described.

40 8. In a vaporizer for internal combustion engines, a mixing chamber, a valve chamber at one side of the mixing chamber and

communicating therewith, an atomizing nozzle extending into the mixing chamber, a conduit communicating with the nozzle and 45 with the valve chamber, an inlet conduit for the liquid fuel extending into the valve chamber and comprising a stand pipe open at its upper end, and a valve in the valve chamber for opening and closing the stand 50 pipe, the valve having a piston slidably fitting the valve chamber and movable to open the pipe by the suction in the mixing chamber, substantially as and for the purpose specified. 55

9. In a vaporizer for internal combustion engines, a mixing chamber, a valve chamber at one side of the mixing chamber and communicating at its upper end therewith, an atomizing nozzle extending into the mixing chamber, a conduit communicating with the nozzle and the valve chamber, an inlet conduit for the liquid fuel extending into the lower end of the valve chamber and including a stand pipe of large diameter compared with the first-mentioned conduit, the stand pipe being contracted at its upper end, and a valve in the valve chamber for opening and closing the contracted end of the stand pipe, the valve having a piston 60 slidably fitting the valve chamber and movable to open the pipe by the suction in the mixing chamber, substantially as and for the purpose set forth. 65

In testimony whereof, I have hereunto signed my name in the presence of two attesting witnesses, at Palmyra, in the county of Wayne, in the State of New York, this 17th day of May, 1910. 70 75
